UNITED STATES PATENT OFFICE

166,803

DESK

Arthur O. Garrett, San Marino, Calif.

Application February 20, 1950, Serial No. 8,022

Term of patent 14 years

(Cl. D33—7)

To all whom it may concern:

Be it known that I, Arthur O. Garrett, a citizen of the United States of America, resident of San Marino, in the county of Los Angeles, State of California, have invented a new, original, and ornamental Design for a Desk, of which the following is a specification, reference being had to the accompanying drawing, forming a part thereof.

In the drawing, Fig. 1 is a perspective view of a desk showing my new design;

Fig. 2 is an end elevation view of the desk.

Fig. 3 is a front elevation view of the desk,

Fig. 4 is a top plan view of the desk; and

Fig. 5 is a bottom view of the desk.

I claim:

The ornamental design for a desk, as shown.

ARTHUR O. GARRETT.
